(57) **CLAIM**

The ornamental design for a chair with a curvilinear frame as shown and described.

DESCRIPTION

FIG. 1 is a left-front perspective of the chair with a curvilinear frame.

FIG. 2 is a left-side view thereof;

FIG. 3 is top plan view thereof;

FIG. 4 is a bottom plan thereof;

FIG. 5 is a front elevation view thereof;

FIG. 6 is a rear elevation view thereof;

FIG. 7 is a cross-sectional view of the chair with a curvilinear frame taken along line 7-7 in FIG. 1; and,

FIG. 8 is a cross-sectional view of the chair with a curvilinear frame taken along line 8-8 in FIG. 1.

The broken lines showing the screws in the drawings are for illustrative purposes only and form no part of the claimed design.

The fragmented crosshatch pattern shown in FIGS. 1-8, including the seat and backrest, represent fabric and is repeated through the areas shown.
